UNITED STATES PATENT OFFICE.

GEORGE A. FREEMAN, OF NEW YORK, N. Y., ASSIGNOR TO BERNARD HECHT,
OF SAME PLACE.

BOX.

SPECIFICATION forming part of Letters Patent No. 242,123, dated May 31, 1881.

Application filed March 22, 1881. (No model.)

To all whom it may concern:

Be it known that I, GEORGE A. FREEMAN, a citizen of the United States, residing in the city of New York, county of New York, and State of New York, have invented certain new and useful Improvements in Boxes, fully described and represented in the following specification and the accompanying drawings; forming a part of the same.

10 In said drawings, Figure 1 is a front elevation of my improvement, shown closed. Fig. 2 is a perspective view of the same, showing the box open for the inspection of its contents, and having one of its compartments partially removed. Fig. 3 is a longitudinal central sectional elevation of the closed box, and Fig. 4 is a cross-sectional elevation on the line $x-x$ of Fig. 3, while Figs. 5 and 6 show, respectively, a sectional elevation and plan of one end of 20 the box open and a modification of the same in cross-section; and Fig. 7 shows a modified form of an end piece.

As heretofore constructed, boxes intended for the reception and display of articles of merchandise, such as pencils, pen-holders, &c., have had but a limited capacity for the display of their contents, and the amount of space utilized for holding the articles so as to allow them all to be exposed to view has not been 30 the largest attainable for the amount of material used and the size of the box.

The object of this invention is to provide a box which shall be compact in itself, hold its contents securely, allow the entire contents to 35 be readily displayed, and at the same time permit any one of the contained articles to be readily removed without disturbing the remainder.

The invention consists in a box constructed 40 of two compartments hinged together, each constructed to hold and display its contents, and each provided with a projecting closed end, which serves to close the opposite open end of the other compartment.

45 The invention further consists in a box constructed of two trays or compartments, each partially closed at its top to form a pocket and hinged to one another with the closed portions at opposite ends of the box.

50 The invention also consists in certain details

of construction, employed for the purpose of holding the contained articles securely and at the same time allowing of their ready removal.

Each tray or compartment A is open at one end, while its opposite end is closed by a piece, B, extended beyond the body of the tray, so that when the trays are shut together it will close the opposite end of the other tray.

Each piece B is provided, as shown, with a sloping brace-piece extending along the side 60 of the box toward its center. These brace-pieces are attached to the outside of each tray, and do not come within the line of the outer edge, so that the straight edge of the opposite tray when the trays are closed together passes 65 inside of the brace-piece, as shown in Fig. 1. This brace-piece might be dispensed with, as it performs no service in closing the open ends of the trays, but is simply for the purpose of strengthening the extension B.

70 The tops of the trays are partially closed by retaining-strips C, which, as placed, form, in conjunction with the sides, the bottom, and the closed ends, pockets for holding the ends of the contained articles in place. Said strips 75 also provide spaces for labels or any descriptive matter, and may be ornamented as desired. These strips may be placed at other points, although the position shown is the most desirable for purposes of strength, while it 80 also allows the pencils or other articles to be removed without much longitudinal movement.

85 The pencils or other objects may be placed directly in the open-ended trays or compartments, although I prefer to use additional means for preventing them from sliding from the box prematurely when it is opened. For this purpose an additional tray or holder, D, may be fitted friction-tight within the compartment A. The end of the tray D, which is closed at the open end of A, prevents the pencils or other objects from sliding out of the box. When a pencil is to be removed the tray 90 D is slid out sufficiently to bring the ends of the pencils from beneath the retaining-piece C, when either may be readily removed without disturbing the remainder.

95 Instead of the sliding tray with closed end, if preferred a movable end piece applied to 100

the compartment A itself may be used. Such a device is shown in Figs. 5, 6, and 7.

The end piece, H, is hinged to the bottom of the compartment A, and is held by elastic 5 attachments G, secured to the sides of A and to the piece H. To remove a pencil the end piece, H, is swung outward and downward, and the pencil may be then slid longitudinally until disengaged from the retaining-strip. The 10 attachment G afterward returns the end H automatically to place.

The end piece, M, Fig. 7, consists of an L-shaped piece hinged to the bottom of the compartment A.

15 The ends of the pencils rest in the angle of the end piece, L, which prevents them from readily slipping out of place. By tipping the piece into the position shown in dotted lines the pencils or other objects may be removed.

20 The sliding trays and boxes may be lined with velvet and other similar material, and the box itself may be constructed of wood, cardboard, or such other material as taste may dictate.

25 What I claim is—

1. A packing box or case for pencils or analogous objects, constructed of two compartments hinged together, each of said compartments of a depth sufficient to contain a single layer 30 only, and each constructed with one end closed and the other end movable, substantially as described.

2. A box composed of two compartments hinged together, each of said compartments consisting of an open tray permanently closed 35 at one end, and provided at its other end with a hinged piece, substantially as described.

3. A box composed of two hinged compartments, each constructed with a permanently-closed end and a hinged spring end, substantially 40 as and for the purpose described.

4. A box composed of two trays or compartments hinged to one another, each constructed to hold and display its contents, and each provided with a projecting end that serves to 45 close the opposite end of the other tray.

5. In a box constructed to hold and display its contents, the combination of two compartments hinged to one another, each having a projecting end piece and a hinged or movable 50 end piece, substantially as and for the purpose described.

6. A box composed of two trays or compartments hinged to one another, and each provided with a retaining strip or piece at the 55 end which is opposite to the open end of the other tray.

In testimony whereof I have hereunto set my hand in the presence of two subscribing witnesses.

GEO. A. FREEMAN.
